UNITED STATES PATENT OFFICE.

CLARENCE R. HECKFORD, OF OAKEN, ENGLAND.

LOCK AND LATCH CASE.

SPECIFICATION forming part of Letters Patent No. 634,688, dated October 10, 1899.

Application filed May 18, 1899. Serial No. 717,325. (No model.)

To all whom it may concern:

Be it known that I, CLARENCE ROBERT HECKFORD, a subject of the Queen of Great Britain, residing at Oaken, near Wolverhampton, in the county of Stafford, England, have invented certain new and useful Improvements in Lock and Latch Cases, of which the following is a specification.

This invention relates to means for securing the back or cap plate to the case of a lock or latch. Ordinarily this has been effected by screws passing through the back plate and driven into the front plate of the case. This means of securing the back plate is relatively costly and has other obvious disadvantages; and the object of the present invention is to provide a simple, efficient, and inexpensive means for securing said back plate of the case without the aid of screws, whereby the objections to the means heretofore employed are obviated.

The invention lies in the utilization of the spring of the sheet metal forming the upright walls of the lock-case for effecting the engagement of reciprocally-interlocking parts in or on the said walls of the case and on the back plate for securing said plate in place.

The invention is illustrated in the accompanying drawings, in which—

Figure 1 is a rear elevation of a sheet-metal lock or latch case with the cap or back plate fixed thereto according to this invention. Fig. 2 is a detached view of the cap-plate. Fig. 3 is a section of the case, taken on line x^3 in Fig. 1, the back plate being omitted. Fig. 4 is a section of the case, taken on line x^4 in Fig. 1, and also with the back plate omitted. Fig. 5 is a longitudinal section taken on line x^5 in Fig. 1, but showing the back plate in position for being pressed down into place. Fig. 6 is a transverse section taken through a lock or latch case on line x^6 in Fig. 7, illustrating a modified form of the invention; and Fig. 7 is a longitudinal section of the same at line x^7 in Fig. 6.

Referring primarily to Figs. 1 to 5, A is the back plate; C, the case; B, the inner end wall thereof, and D the outer or front end wall thereof. These are formed of sheet metal.

On one end of the back plate A are formed short projections or tenons c, adapted to en-

gage apertures or mortises c' in the end wall B of the case C, and on the other end of said plate A is formed a similar short projection or tenon d, adapted to engage an aperture or mortise d' in the end wall D of the case C. By preference there will be two tenons c and one tenon d; but the actual number used is not important to the invention.

Where the case C is made from sheet metal, it will be cut or punched to the proper shape, with the proper apertures for the knob-spindle and bolts, as indicated at e, e', and e'', and the mortises c' and d' will be punched out, the side and end walls will be bent up, and these will usually be simply brought together at the corners of the case without being secured together.

In placing the back plate A the tenons c will be engaged with the mortises c', as seen in Fig. 5, when the tenon d on the inclined back plate will rest against the end wall D of the case C. Pressure is now applied on the back plate, the end wall D yields outward elastically, and the tenon d is made to engage or snap into the mortise d', which permits the end wall D to resume, by its resiliency, its proper upright position, and the engagement of the tenons with their mortises holds the back plate firmly in place. This plate can be removed by springing outwardly the end wall or walls of the case, so as to free the tenon or tenons at one end of the plate.

Should the end wall D be secured at its lateral edges to the side walls of the case C, it will still yield sufficiently to allow the back plate to be placed and secured.

Referring now to Figs. 6 and 7, this construction shows inclined projections f and f' on the inner faces of the respective end walls B and D in lieu of mortises, and these projections may be formed by pressing out the sheet metal of the parts. The back plate A' has no tenons on its ends; but at its lateral margins it is formed, as seen at g, to take over and rest on the side walls of the case C and also to take between them. The back plate is pressed down, as in the first instance, and wipes over the inclined projection f' and snaps in under it. The lateral rabbeted edges g on the back plate serve to prevent lateral movement and to uphold the back plate. The

number of projections f and f' on the end walls is not very important. One of each would serve.

The walls B and D have been referred to 5 herein as "end walls" merely in a descriptive sense. If the lock-case were square, the walls would all be side walls.

The shoulders on the end walls--that is to say, the mortises c' and d' or the projections f and f' --will of course be formed primarily on the case C, so that when the back plate is sprung into place the attachment will be complete and no subsequent driving of screws or riveting will be required.

15 Having thus described my invention, I claim—

1. A lock or latch case having end walls, one of which is capable of being sprung outward elastically, and having a back plate held 20 in place by engagement at its ends under shoulders primarily formed on the said end walls, substantially as set forth.

2. A lock or latch case having end walls,

one of which is capable of being sprung outward elastically, and having mortises primarily formed in said end walls, said case having 25 a back plate provided at its ends with tenons which engage said mortises, substantially as set forth.

3. A lock or latch case of sheet metal having opposite walls, B and D, one at least of which is capable of being sprung outward elastically, and said walls having in them primarily-formed mortises as described, and said case having its back plate A held in place 30 by short tenons on its opposite edges engaging the mortises in the said walls, substantially as set forth.

In witness whereof I have hereunto signed my name, this 6th day of May, 1899, in the 40 presence of two subscribing witnesses.

CLARENCE R. HECKFORD.
